ARTIFICIAL RESPIRATION BY ELECTRONIC
STIMULATION

Stanley J. Sarnoff, Boston, Mass.

Application August 20, 1949, Serial No. 111,424

7 Claims. (Cl. 128—421)

1

This application is a continuation in part of my application Number 399, filed January 3, 1948, now abandoned.

This invention relates to a method of stimulating a physiological function of an individual and more particularly to the inducing of artificial respiration.

The methods of inducing artificial respiration employed heretofore have been based on the principle of mechanically applying a cyclic pressure to the pulmonary cavities. This is done directly by forcing air or oxygen into the lungs via the nasopharynx and the trachea, or indirectly by enclosing either the chest or the entire body with the exception of the head and neck and cyclically pressurizing the enclosure so that the resulting chest movement stimulates natural breathing.

Although these methods successfully induce artificial respiration the apparatus required is large, expensive and complicated so that its use is largely confined to institutions and clinics. The patient is restricted in his movements by the enclosing apparatus and nursing care and medical examination are made correspondingly difficult. The size of much of this type of apparatus prevents it from being readily portable and limits its use in emergencies and at remote locations. The high cost limits the number of units available for use during an epidemic. An important physiological consideration is that all these methods respiration the patient by means of positive pressure breathing which is directly contrary to normal breathing. The method about to be described causes respiration by rhythmically producing a negative intrapleural pressure just as in spontaneous respiration.

The objects of this invention are to provide a method and apparatus which induces artificial respiration in a simple and natural manner, which does not limit the movement of the patient, which does not cause pain to the patient, which is small and convenient to use, which is readily portable and can be used anywhere, which is inexpensive to construct and which generally improves the stimulation of a physiological function of an individual by applying to a nerve trunk a cyclically varying potential which recurrently rises

art of respirator manufacture.

In a broad aspect the invention contemplates above the threshold value of the individual and

2

alternately falls to or below said value, the threshold value being that at which the diaphragm (or other part or parts to be stimulated) responds to the stimulus. Preferably each cycle of potential comprises a plurality of pulses which gradually increase in amplitude to a maximum and then gradually decrease. Throughout each cycle the pulses may be separated by gaps or the cycles may be separated by gaps or both. While 5 the potential may fall to zero in the gaps, it need fall only to the region of the threshold value. The physiological effectiveness of the stimulation may be adjusted to the needs of different individuals and different ailments by varying the amplitude of the pulses; the duration of the pulses, the length of the gap (if any) between successive pulses, the amplitude of the cycles, the length of each cycle, or the length of the gap (if any) between successive cycles or any combination of these variables.

While the potential may be applied magnetically or electro-magnetically, as for example by transmitting impulses from an external source to a small magnetic or radio receiver located partly or wholly inside the patient, it is preferably applied conductively by means of spaced contactors applied at spaced locations to the skin of the individual or directly to the nerve in the form of probes. Excellent results have been obtained with probes applied directly to the phrenic nerve, but I have also found that it is possible to consistently obtain satisfactory respiration approximating normal spontaneous respiration, both as regards appearance of the respiratory effort and the physiologic effect on ventilation and circulation, by connecting the source of cyclically varying potential to a pair of electrodes, one of which is applied to the skin overlying the course of the phrenic nerve, so that the potential is applied to the nerve trunk indirectly through the skin. The second electrode is placed at some other point on the surface of the body, such as the back of the neck, with the result that the path of the stimulating current includes a portion of the 10 phrenic nerve or one of its anatomical roots. The electrode closest to the nerve preferably makes contact with the skin over a relatively small area, while the second electrode may make contact over a relatively large area of the skin. The small-contact electrode is used as an exploring elec-

trode to find the position which produces most satisfactory stimulation of the phrenic nerve.

It is similarly possible to cause ventilation of the lungs by cyclically stimulating the nerves to abdominal muscles which, upon contracting, force air out of the lungs, and, upon relaxing, permit air to reenter the lungs.

The peak voltage required to excite the motor fibers to the diaphragm or other muscles varies from patient to patient and from site to site on the same patient. This peak voltage required for motor fiber stimulation however, is below the threshold necessary to excite pain fibers and therefore effective respiratory activity can be produced without eliciting pain. When the potential is applied through the skin 5 to 20 volts are usually required but when applied directly to a nerve by a probe a fraction of a volt (say one-half volt) is usually sufficient.

For the purpose of illustration, typical embodiments of the invention are shown in the accompanying drawing in which

Fig. 1 is a wiring diagram of one embodiment of the invention;

Fig. 2 is an isometric view of one form of the probe;

Fig. 3 is a diagram of a typical potential wave as a function of time such as is obtained from the embodiment shown in Fig. 1;

Fig. 4 is a wiring diagram of another embodiment;

Fig. 5 is a diagram showing the wave shape of the potential delivered by the oscillator to the pulse generator at the line 5-5 of Fig. 4;

Fig. 6 is a diagram showing the wave shape of the potential delivered by the pulse generator at the line 6-6 of Fig. 4;

Fig. 7 is a diagram showing the wave shape of the potential delivered to the potentiometer at the line 7-7 of Fig. 4; and

Fig. 8 is a diagram of the potential delivered by the potentiometer to the patient at the line 8-8 of Fig. 4.

In the particular embodiment of the invention chosen for the purpose of illustration a cyclic electrical potential for stimulating the phrenic nerve (or other nerves) of an individual is obtained from a vacuum tube oscillator Os and a square wave generator G which may be of any of the types well-known to those skilled in the art. The connection between the oscillator Os and the generator G is accomplished by joining a plate p_1 of the oscillator vacuum tube VI to a generator input terminal t_1 and a tube cathode k_1 to a generator input terminal t_2 by the leads 11 and 12 respectively. Between a tube control grid g_1 and the cathode k_1 is connected an oscillator tank circuit including a choke L_1 in parallel with a variable capacitor C_1 . Connected between the generator terminals t_1 and t_2 is the output circuit of the oscillator which includes a capacitor C_2 in parallel with a choke L_2 . The circuit elements of the oscillator Os and the generator G are proportioned so that a cyclic potential having a square wave with a pulse duration of .001 of a second is obtained across the generator output terminals t_3 and t_4 . The output of the generator G is adjustable by any of the well-known means to give pulses with a peak potential which is variable between 0.0 and 60 volts.

The desired duration of the periodic variations in the peak potential are obtained by means of a regulator such as a potentiometer R_v which includes a rotatable contact 13, an insulating segment 14 and a tapped winding 16. The taps of

the winding 16 are alternately connected to the terminal t_3 by a rotary switch 8 and a wire 17. A wire 18 branches from the other end 15 of the winding 16 to connect with a generator output terminal t_4 and a cathode k_2 of a vacuum tube v_2 . A grid g_2 and a plate p_2 of the tube v_2 are joined by a wire 19 to one of the probes P of the probe support S (Fig. 2) which will be described in detail hereinafter. The other probe P is connected to the rotatable contact 13 of the potentiometer R_v by a wire 20.

The rotatable tap 13 is driven by a geared motor M which is connected to the power supply terminals a and c. To control the speed of the motor M, its shunt field F is connected in series with a variable resistor r across the terminals a and c.

As is shown in Fig. 2 the probe support S includes a trough 21 molded of yieldable insulating material such as semi-hard rubber. The trough 21 is semicircular in shape and has fastened to the inner surface thereof two metallic probes P which are connected to the flexible wires 19 and 20 respectively. The probes P are located in two respective planes which intersect the axis of the cylinder with a spaced relationship of approximately one centimeter therebetween. The trough inside and the probes P are so positioned as to form substantially a smooth surface to contact the sheath of the phrenic nerve N to which the stimulus is being applied.

A small slit is made in the neck of the patient so that the phrenic nerve N is exposed. The probe support S is then slipped under the nerve N cradling it as is shown in Fig. 2. As the probe P projects above the inner surface of the support trough 21, the nerve N is subjected to whatever electrical potential is applied across the probes P.

To induce respiration a cyclic potential is applied to the probes P with characteristics as is shown in Fig. 3. This potential comprises a series of square pulses w with peak values which are varied so that the envelope e is formed. When the pulse w_1 is applied, the low peak value of the potential stimulates only a few of the fibers of the phrenic nerve N and the respective muscular segments in the diaphragm controlled by these fibers contract. As the peak voltage of the successive pulses w increases, more and more of the fibers in the phrenic nerve are stimulated and therefore more and more of the muscular segments of the diaphragm contract until the diaphragm as a whole undergoes a forceful contraction to expand the pleural cavity thereby drawing air into the lungs. The cessation of stimuli as the voltage returns to a constant low or zero value (as at 0 after the pulse w_p , Fig. 3) results in relaxation of the diaphragm and a decrease in the size of the pleural cavity thereby allowing air to be expelled from the lungs. The sequence of constant low, gradually increasing and suddenly decreasing periods is then repeated.

The frequency of the pulses w, the maximum amplitude of the pulse w_p , and the relative duration of the low potential and increasing potential periods are independently adjustable in accordance with the constitutional requirements of the patient as will be described hereinafter so that a normal breathing rate is attained. If the normal breathing rate is not known, experimental adjustments are made at low values which are gradually increased until the patient's appearance, for example the skin color and respiratory movement indicates that sufficient oxy-

gen is being taken up by the blood and sufficient carbon dioxide is being blown off.

To generate the wave shape shown in Fig. 3 a sine wave from the oscillator Os is applied across the input terminals t1 and t2 to lock in the generator G. The resulting output at the generator terminals t3 and t4 is a series of square wave pulses w with a duration of .001 second and the same frequency as that of the sine wave. A regulator such as the capacitor C1 is adjusted so that the frequency of the sine waves from the oscillator Os and therefore the frequency of the square pulses w is in the region of from 5 to 60 cycles per second with a usual frequency of approximately 40 cycles per second, the optimum being determined as described above. The output of the generator G is adjusted so that an optimum peak potential w_p is obtained in the range of from 0.1 to 60 volts. The tube V2 is used as a current limiting device so that the probe current is always limited to a safe value.

The envelope e is developed by rotating the tap 13 of the potentiometer Rv clockwise by means of the geared motor M. As the tap 13 contacts the insulating segments 14 no connection is made and the potential between the probes P is zero as indicated at 0 in Fig. 3. When the tap 13 first contacts the winding 16 as at 15 a pulse across the probe P such as w_1 (Fig. 3) results. As the tap 13 progresses the resistance in series with the probe circuit decreases so that successive pulses w have peaks of increasing magnitude. When the point is reached where no resistance remains in the probe circuit and the pulse w_p has a maximum peak value of approximately the same value as the peak potential of the pulses appearing across the generator terminals t3 and t4, the tap 13 then again contacts the insulating segments 14 and the potential across the probes P drops to zero. This sequence is repeated during successive rotations of the tap 13.

The frequency of the repetition of the sequences is controlled by the speed of the geared motor M, the output shaft speed of which can be varied from approximately 6 to 60 revolutions per minute thereby to give the optimum respiratory period duration in the range of from one to ten seconds. Adjustment of the absolute duration of the increasing potential period is obtained by means of the switch s.

The second embodiment of the invention shown in Fig. 4 comprises a vacuum tube V1a having a coil L2a in its plate circuit which is magnetically coupled with a coil L1a in the grid circuit of the tube so that the feed back causes the tube to go into oscillation. The bias for the tube grid is supplied by a leak resistor r1 and a capacitor c3 in the usual manner. The output of the oscillator, which varies according to the sine law as is shown in Fig. 5, appears at line 5-5 of Fig. 4.

The oscillator output is used as a trigger for a pulse generator being connected thereto by means of a coupling capacitor c4. The generator comprises two vacuum tubes V3 and V4 having their cathodes k3 and k4 connected together and their anodes a3 and a4 connected to the "B+" power supply through the resistors r3 and r4 respectively.

The grid g3 of the tube V3 is normally biased so that the tube conducts in the absence of a negative input signal from the oscillator. Such bias is obtained by connecting a bleeder resistor r6 across the "B+" power supply. The resistor r6 is provided with two adjustable taps x1 and

x2. Tap x1 is linked directly with the cathodes k3 and k4. Tap x2, which is adjusted to a more negative potential than the tap x1, is connected to the grid g3 by the resistors r7 and r8. The grid is also coupled to the anode a4 of the tube V4 by a capacitor c6. The grid g4 is linked to the common junction of resistors r9 and r11 which are connected in series between the anode a3 and ground whereby with the tube V3 conducting the grid g4 is sufficiently negative so that the tube V4 is nonconducting.

The coupling capacitor c4 of the oscillator is connected to the common junction of the resistors r7 and r8 so that during the negative portion of the output wave the grid g3 is driven negative with respect to cathode k3 to stop the current flow through the tube V3. The potential upon the grid g4 thereupon becomes more positive so that the tube V4 conducts drawing current through the resistor r4. The resulting voltage drop across resistor r4 causes current to flow through the resistors r7 and r8 thereby gradually increasing the potential impressed upon the grid g3 until after a time interval determined principally by the time constant of the series connected capacitor c6 and the resistors r7 and r8 and to a lesser extent by the ohmic characteristic of r4 and the "B+" supply voltage, the grid g3 becomes sufficiently positive so that the tube V3 again conducts. The voltage drop across r3 thereby impresses a relatively negative potential upon the grid g4 to cut off the tube V4. By making the ohmic value of the resistor r4 relatively small with respect to the total ohmic value of the resistors r7 and r8, so that the current charging the capacitor c6 does not substantially affect the magnitude of the voltage drop across the resistor r4, a rectangular voltage pulse is produced across r4 which is similar in shape but has a lower peak value than the potential wave illustrated in Fig. 6. The period of the pulses across resistor r4 can be changed by varying either the value of the resistor r7 or the capacitance of c6 thereby to change the time constant of the R.-C. circuit.

The rectangular potential wave is applied to the grid g5 of an amplifier tube V5 by means of a coupling capacitor c7 and a tapped resistor r12 which are connected in series between the anode a4 and ground. The grid g5 is linked to the tap to make the gain of the amplifier adjustable thereby determining the peak amplitude of the pulses shown in Fig. 6. Bias for the grid g5 is supplied by a resistor r13 connected between the cathode k5 and ground. The "B+" potential for the anode a5 is supplied through a resistor r16.

The output of the amplifier is fed to a peaking circuit comprising a capacitor c8 which is connected between one end of the parallel windings r14 and r15 of a potentiometer Rv1. The opposite end of the windings r14 and r15 are grounded. Both the capacitance of the capacitor c8 and the parallel resistance of the resistors r14 and r15 are made small whereby the time constant of their series combination is short so that successive discontinuities in the square wave potential applied thereto alternatively charge and discharge the capacitor c8 through the potentiometer Rv1. The capacitor charging and discharging current flows through the potentiometer Rv1 are in opposite directions so that the voltage drop across the windings r14 and r15 is a series of alternatively positive and negative sharply peaked pulses having the form shown in Fig. 7.

The electrodes p_1 and p_2 for cyclically applying the peaked pulses to the patient's body are connected respectively to the rotatable arm 131 of the potentiometer Rv_1 and ground.

As described heretofore with respect to the first embodiment, modulation of the peaked pulses shown in Fig. 7 is accomplished by rotating the arm 181 of the potentiometer $Rv1$ in a clockwise direction by means of a motor $M1$ thereby to obtain a cyclic variation of the peak amplitude of the pulses having an envelope similar to that shown in Fig. 8.

When the arm 131 of the potentiometer Rv1 is in its bottom position the potential between the electrodes p_1 and p_2 is zero as at 0' (Fig. 8). As the potentiometer arm 131 moves upwardly the electrode potential gradually increases to a peak e' when the arm 131 reaches the junction of resistors $r14$ and $r15$. As the arm 131 descends along winding $r15$ more and more resistance is cut into the circuit so that the electrode potential is reduced. As the winding $r15$ is considerably shorter than the winding $r14$ the arm 131, which moves at a uniform rate, drops the electrode potential to zero (0'', Fig. 8) in a shorter time than the interval required for the potential to rise to the peak potential e' . The zero potential dwell period between points 0' and 0'' in Fig. 8 results when the arm 131 is grounded during contact with the low resistance portion 141.

The probe electrodes p_1 and p_2 may be similar to the probe P shown in Fig. 2 which is applied directly to the nerve trunk or may be surface electrodes of the conventional type applied to the skin adjacent the nerve whereupon the peak potential applied must be raised. By adjustment of the pulse frequency, the maximum amplitude of the stimulating potential, relative duration of the increasing voltage and decreasing voltage phases of the respiratory cycle, as described heretofore, a respiratory cycle meeting the constitutional requirements of the patient is attained. The appearance of the patient, for example the skin color and respiratory movement, will indicate when sufficient ventilation is occurring. This may be more quantitatively determined by determination of blood pH or gas content or gas tensions or analysis of the patient's expired air.

In the specific embodiments described above the magnitude of the diaphragmatic contraction, and thus, the depth of respiration, is set by the amplitude control on the pulse generator, while the respiratory rate is controlled by the motor speed. In some cases it may be found advantageous to employ a pulse frequency which varies with the variations in peak potential. This variation can be obtained by coupling the pulse frequency control to the motor shaft. Although the embodiments described above show a separate oscillator and pulse generator it is entirely feasible to use a self-excited pulse generator, or to obtain the rectangular pulses directly from a sine wave source A. C. by suitable clipping and shaping circuits, or by a mechanically driven contactor. The embodiments described above show mechanically driven potentiometers for modulating the effective value of the stimulating potential; but it has also been found feasible to obtain such modulation by non-mechanical methods, for example electron tube circuits.

It should be understood that the present disclosure is for the purpose of illustration only and that this invention includes all modifications

and equivalents which fall within the scope of the appended claims.

I claim:

1. The method of artificially inducing respiration which comprises applying to the nerve trunk controlling respiration of an individual a cyclically varying electric potential which during each cycle rises to a point above the threshold value of nerve stimulation of the individual and then falls substantially to or below said value and remains substantially at or below said value for a portion of the cycle to permit exhalation.

15 2. The method of artificially inducing respiration which comprises applying to the nerve trunk controlling respiration of an individual a cyclically varying electric potential which during each cycle rises to a point above the threshold value of nerve stimulation of the individual and then falls substantially to or below said value, each 20 cycle comprising a succession of pulses, the amplitude of successive pulses gradually increasing and then decreasing during each cycle, the duration of the portion of each cycle following said point permitting exhalation.

25 3. Apparatus for artificially inducing respiration which comprises a generator of cyclic electric potential, electrode means for applying said potential to a nerve trunk, a control network connecting said electrode means to said generator,
30 said network being adapted to gradually increase the peak value of the potential, quickly reduce it, hold it at the reduced value and in sequence repeat the increasing reducing and holding periods, and regulator means in said network for varying the relative durations of the increasing and holding periods.

4. Apparatus for artificially inducing respiration which comprises a generator of cyclic electric potential, electrode means for applying said potential to a nerve trunk, a control network connecting said electrode means to said generator, said network being adapted to gradually increase the peak value of the potential, quickly reduce it, hold it at the reduced value and in sequence repeat the increasing reducing and holding periods, a regulator for varying the frequency of the generator, and a regulator in said network for varying the relative durations of the increasing and holding periods.

5. Apparatus for artificially inducing respiration which comprises an electric circuit, means in said circuit for supplying for application to a nerve trunk of an individual, a cyclically varying potential which during each cycle rises to a peak above the threshold value of nerve stimulation of the individual and then falls substantially to or below said value, said means including a generator and a regulator to vary the rate of said cyclic variation, and means in said circuit for varying the length of the potential-rising portion of each cycle independently of the length of the cycle.

6. Apparatus for artificially inducing respiration which comprises an electrical circuit, means in said circuit for supplying for application to a nerve trunk of an individual, a cyclically varying potential which during each cycle rises to a peak above the threshold value of nerve stimulation of the individual and then falls substantially to or below said value, each cycle comprising a succession of pulses, the amplitude of successive pulses gradually increasing and then decreasing during each cycle, said means including a generator and a regulator to vary the rate of

said cyclic variation, and means in said circuit for varying the length of the potential-rising portion of each cycle independently of the length of the cycle.

7. Apparatus for artificially inducing respiration which comprises an electrical circuit, means in said circuit for supplying for application to a nerve trunk of an individual, a cyclically varying potential which during each cycle rises to a peak above the threshold value of nerve stimulation of the individual and then falls substantially to or below said value, each cycle comprising a succession of pulses, the amplitude of successive pulses gradually increasing and then decreasing during each cycle, said means including a generator and a regulator to vary the rate of said cyclic variation and a regulator to adjust said peak value, and means in said circuit for vary-

ing the length of the potential-rising portion of each cycle independently of the length of the cycle.
